UNITED STATES PATENT OFFICE.

JOHN R. O'CONNELL, OF WILLOW, OKLAHOMA.

ADJUSTABLE REVOLVING GROCER'S CABINET.

949,944.

Specification of Letters Patent. Patented Feb. 22, 1910.

Application filed May 15, 1909. Serial No. 496,143.

To all whom it may concern:

Be it known that I, JOHN R. O'CONNELL, a citizen of the United States, residing at Willow, in the county of Greer and State of Oklahoma, have invented a new and useful Improvement in Adjustable Revolving Grocer's Cabinets, of which the following is a specification.

This invention relates to grocers' cabinets especially adapted to be used for dispensing granulated articles, the object being to provide a cabinet which is revolubly mounted and has a plurality of receptacles for holding sugar, beans, peas and the like whereby the same can be readily delivered into a bag arranged upon a pair of scales without handling the same.

A further object of my invention is to provide a cabinet which is so constructed that any one of the receptacles can be readily detached so as to refill it when the contents have been dispensed.

A still further object of my invention is to provide a cabinet which can be easily and quickly attached to the ordinary counter, it simply being necessary to form an opening in the counter to allow the supporting shaft to pass through which is mounted on an adjustable bearing.

A still further object of my invention is to provide a support for the receptacles which has a plurality of spouts provided with cut-offs, said spouts being adapted to register with openings formed in the bottoms of the receptacles, said openings being also closed by cut-offs so that when it is desired to remove one of the receptacles the same can be readily detached without any danger of spilling any of the contents.

A further object of my invention is to provide an adjustable funnel in connection with the cabinet, said funnel being carried by adjustable arms under the support whereby the contents of any one of the receptacles can be delivered into a bag arranged on the scales.

A still further object of my invention is to provide means for adjusting the supporting shaft vertically in order that the same can be readily adjusted to suit different height counters.

With these objects in view, my invention consists of the novel features of construction, combination and arrangement of parts hereinafter fully described, pointed out in

the claims and shown in the accompanying drawings, in which,

Figure 1 is a side elevation of my improved cabinet, showing the application of the same, the cabinet being partly shown in section. Fig. 2 is a section taken on line 2-2 of Fig. 1. Fig. 3 is a top plan view of the cabinet, half of the covers being removed. Fig. 4 is an enlarged vertical section through the supporting platform and receptacles and, Fig. 5 is a perspective view of the supporting platform.

In carrying out my improved invention I employ a tubular shaft A adapted to pass through an opening B formed in the counter, said shaft resting on a collar C adjustably mounted on a pin D by a set screw C', said pin being provided with a pointed lower end having square sides adapted to fit within a square socket E secured on the floor under the opening of the counter and it will be seen that by adjusting the collar on the pin the shaft can be adjusted vertically. By this arrangement the shaft can be readily detached by simply drawing the same upwardly. To support the upper end of the shaft or hold the same vertically I provide a pin F carried by a plate F' provided with openings, said plate being adapted to be secured to the ceiling or other suitable support above the shaft so that the pin will extend down into the same and hold the shaft steadily so as to prevent the same from becoming knocked over by a sudden blow.

Fixed on the shaft A is a circular supporting plate G which is provided with radial strips G' and is supported by arms G² which are connected to the shaft so as to relieve the plate of the strain as will be herein-after fully described. The circular plate is provided with a plurality of openings under which are secured spouts H provided with pivoted cut-offs H' having handles H² for operating the same and it will be seen that when the cut-offs are in a closed position the spouts are closed so that it will be impossible for anything to pass out of the same.

Mounted on the plate is a plurality of segmental receptacles I provided with openings registering with the openings of the plate and having cut-offs J slidably mounted in their bottoms adapted to close the openings, said cut-offs having handles J' extending outwardly therefrom so as to

allow the cut-offs to be readily operated. These receptacles are adapted to be filled with the granulated material to be dispensed and are closed by removable covers 5 K and in constructing the receptacles I preferably form the same with inclined sides so that when the tops are placed in position they will be held thereon at an inclination so as to give a neat appearance to the same 10 and when the receptacles are in position they fit between the strips and arms so as to form a circular body. The arms extend upwardly between the respective receptacles so that when the receptacles are filled the 15 weight of the same will be taken off of the plate so as to prevent the plate from giving.

The shaft A is provided with a collar L on which is adapted to rest a sleeve M revolvably mounted upon the shaft, said sleeve 20 being provided with spaced apertured ears M' between which is pivotally mounted a pair of arms N on pivot pins N', said arms being pivotally mounted on pins O' carried by a plate P extending outwardly from a 25 funnel Q which allows the funnel to be adjusted as will hereinafter be fully described. These arms are mounted parallel with respect to each other and are connected together by a coil spring R for normally 30 holding the arms in their adjusted position and the funnel is so arranged with respect to the spouts that when the cut-offs are opened the contents will drop into the same so that they will be carried into the bag 35 arranged upon the scales S which are mounted on the counter in such a position with respect to the cabinet that it will not be necessary to handle the materials to be sold as by revolving the shaft so as to bring the 40 receptacle containing the desired material to be sold and then by adjusting the funnel the contents can be delivered into the bag arranged upon the scales.

From the foregoing description it will be 45 seen that I have provided a cabinet provided with means for delivering the contents out of the receptacles into a bag arranged upon a pair of scales without handling the same in any way thereby saving a great deal of 50 time and trouble and also keeping the material to be sold perfectly clean as the receptacles are formed tight so that the contents will not lose their strength especially when the same is used for dispensing coffee and 55 tea or spices of any kind. It will also be seen that by providing the receptacles with cut-offs and the supporting plate with cut-offs all danger of the contents being wasted is prevented as when the cut-off in the 60 receptacle is open the cut-off in the corresponding spout is closed so that a certain amount of tea or coffee is allowed to pass into the spout and then by closing the cut-off in the receptacle and allowing the 65 contents of the spout to pass into the funnel

gradually the correct amount can be delivered into the bag on the scales. It will also be seen that by having the funnel carried by adjustable arms it can be adjusted vertically to suit different sized bags arranged upon 70 the scales.

What I claim is:—

1. In a cabinet of the kind described the combination with a counter, of a shaft revolvably mounted in said counter, a plate fixed 75 on said shaft provided with spouts having cut-offs, segmental receptacles arranged on said plate provided with cut-offs, covers for closing said receptacles and a funnel revolvably mounted under said plate, said funnel 80 being capable of vertical adjustment.

2. In a cabinet of the kind described the combination with a counter provided with an opening, of a shaft mounted in said opening, a socket arranged under said opening, a 85 pin arranged in said socket, a collar adjustably mounted on said pin adapted to support said shaft, a plate carried by said shaft, and a plurality of receptacles mounted on said plate.

3. In a cabinet of the kind described the combination with a revoluble shaft, of means for adjusting said shaft vertically, a plurality of receptacles arranged on a plate carried by said shaft, said receptacles having 95 cut-offs, spouts carried by the plate provided with cut-offs for receiving the contents of the receptacles and a funnel revolvably mounted under said plate.

4. In a cabinet of the kind described the 100 combination with a counter provided with an opening and having a socket secured to the floor under said opening, of a pin arranged in said socket provided with an adjustable collar, a hollow shaft fitting over 105 said pin resting on said collar, a plate carried by said shaft provided with a plurality of spouts, a plurality of segmental receptacles provided with openings in their bottoms registering with the spouts, cut-offs for 110 closing said openings and a funnel revolvably mounted under said spouts for delivering the contents of the receptacles to a bag or the like.

5. In a cabinet of the kind described the 115 combination with a revolvably mounted shaft, of a circular plate fixed on said shaft provided with radial strips and supported by arms, a plurality of spouts carried by said plate provided with cut-offs, a plurality of 120 segmental receptacles arranged on said plate, between said strips and arms having openings formed in their bottoms registering with the spouts of the plate, slidably mounted cut-offs for closing said openings, 125 removable covers for closing said receptacles and a sleeve revolvably mounted on said shaft carrying adjustable arms having a funnel connected to their outer ends.

6. In a cabinet of the kind described, the 130

combination with a revoluble shaft, of a plurality of receptacles carried by the shaft, a collar fixed on said shaft under said receptacles, a sleeve revolvably mounted on said shaft resting on said collar, pivoted arms carried by said sleeve, a spring connecting said arms and a funnel having a plate piv- | otally connected to the other ends of said arms.

JOHN R. O'CONNELL.
